UNITED STATES PATENT OFFICE.

JAMES S. LOCHHEAD, OF PITTSBURGH, PENNSYLVANIA, ASSIGNOR TO JONES & LAUGHLIN STEEL CORPORATION, OF PITTSBURGH, PENNSYLVANIA, A CORPORATION OF PENNSYLVANIA.

METAL BEAM.

Original application filed March 3, 1923, Serial No. 622,535. Divided and this application filed May 13, 1924. Serial No. 713,052.

To all whom it may concern:

Be it known that I, JAMES S. LOCHHEAD, a citizen of the United States, residing at Pittsburgh, county of Allegheny, State of Pennsylvania, have invented an Improvement in Metal Beams, of which the following description, in connection with the accompanying drawings, is a specification, like characters on the drawings representing like parts.

This invention relates to metal beams suitable among other uses for replacing wooden joists and rafters in the construction of residences and buildings where light loads prevail.

This invention aims to provide a light weight I-section rolled metal beams of much greater strength and stiffness than any solid web I-beams of the same weight heretofore made.

Further aims and advantages of the invention appear hereinafter in connection with the illustrative embodiments thereof shown in the accompanying drawings, wherein

Figs. 1 to 5, inclusive, illustrate metal joists embodying my invention.

In the drawings the relative dimensions are shown or expressed in percentages of the depth for convenience in making comparisons, the dimensions shown being actual dimensions of preferred shapes.

In the particular embodiments of my invention selected for illustration herein the I-beam shown in each figure comprises a web having a thickness (t) not greater than one-tenth of an inch plus one-tenth of the beam depth (d) divided by twelve. This relationship may be expressed as follows:

$$t \geq \frac{1+d/12}{10}$$

where all dimensions are in inches. Also, in the illustrative examples shown, the breadth (b) of each flange is not greater than twenty times the thickness of the web, and may be expressed as follows:

$$b \geq 2 + \frac{d}{6}$$

Preferably the flange breadth is about six-

teen to twenty times the web thickness of beams within the range of sizes shown in the drawings, the ratio being preferably less in the smaller sizes.

For example, in Fig. 1, the I-beam has a depth of nine inches, the thickness of the web 5 is .125 inches, which equals 1.4% of the depth, and the width of the flanges 6 is 2.335", which is 25.9% of the depth.

In Fig. 2, the I-beam has a depth of twelve inches, the thickness of the web 7 is .147", which equals 1.20% of the depth, and the width of the flanges 8 is 3.083", which is 25.7% of the depth.

In Fig. 3, the I-beam has a depth of six inches, the thickness of the web 9 is .120", which equals 2% of the depth, and the width of the flange 10 is 1.756", which is 29.2% of the depth.

In Fig. 4, the I-beam has a depth of five inches, the thickness of the web 11 is .113", which equals 2.26% of the depth, and the width of the flanges 12 is 1.965", which is 39.3% of the depth.

In Fig. 5, the I-beam has a depth of four inches, the thickness of the web 13 is .106", which equals 2.65% of the depth, and the width of the flanges 14 is 1.952", which is 48.8% of the depth.

These relative dimensions of the web thickness and flange breadth of beams embodying my invention are fifty to sixty per cent less than the corresponding dimensions of standard I-beams of the same depths of even the lightest sections rolled; accordingly the weight of my improved beams is correspondingly less than that of standard sections of the same depth, and more nearly approximates the weight of wooden joists two inches thick and of the same or slightly greater depths, for which joists beams of my invention may advantageously be substituted.

As is well known, the deflection of a beam under a given safe load varies inversely with the moment of inertia, and the safe load varies directly with the modulus of rupture; hence it is desirable to shape the beam so as to give values for the moment of inertia and modulus of rupture as large as possible consistent with the practicable

limitations of manufacture by rolling processes.

The proportions of the several beams shown in the drawings as illustrative of my invention, are such as to produce very much greater values for the moment of inertia, modulus of rupture and radius of gyration compared to the weight of the beam per foot than for existing rolled metal beams of any-
10 thing like the same weight.

As compared with wooden joists, rolled beams embodying my invention not only are far superior for fireproof construction but they are slightly stronger for the same weight,
15 and have the further advantage of being shallower for the same strength and stiffness, for all span lengths usual for floors in buildings as commonly designed; and the built up sheet metal beams are in-
20 feerior to mine in transverse strength and stiffness and are also much more expensive to manufacture.

Beams illustrating my invention possess the advantages of great stiffness combined
25 with light weight, making them suitable for longer spans than either standard I-beams or channels of the same weight per foot, and thereby enabling a lighter and stronger floor to be constructed than has heretofore been
30 possible with rolled beams.

Prior attempts to produce light weight flanged beams have been directed toward a reduction in the thickness of the web without a corresponding reduction in the thickness and width of the flanges. The beams thus produced have a tendency to buckle in the web and attendant difficulties due to the relatively greater preponderance of metal in the flanges of such beams than in
35 the standard beams. My invention avoids these difficulties by maintaining approximately the relative proportions between web thickness and flange area found satisfactory for standard beams of similar sizes.

40 My improved beams may be made from suitably shaped blanks by adapting known methods and devices for metal rolling. Other methods that may be used advanta-
45 geously are disclosed in co-pending applica-
50 tions for Letters Patent of the United States; but my invention is not restricted to any particular process.

This application is a division of my application Serial No. 622,535, filed March 3,
55 1923, and a continuation of my application Serial No. 655,091, filed August 1, 1923.

Having described several illustrative em-
60 bodiments of my invention, without limit-
ing myself thereto, what I claim and desire to secure by Letters Patent is as follows:

65 1. A rolled solid web I-beam having a depth not over 12" and not under 4", and a web thickness not over one-tenth of an inch plus one one-hundred-and-twentieth of

the depth, and a flange width proportional to the web thickness, said proportion varying with the depth.

2. A rolled solid web I-beam having a depth not over 12" and not under 4", and a web thickness not over one-tenth of an inch plus one one-hundred-and-twentieth of the depth.

3. A rolled solid web I-beam having a depth not over 12" and not under 10", a thickness of web not greater than 1.8% of the depth and a flange width not greater than 39.6% of the depth.

4. A rolled solid web I-beam having a depth not over 10" and not under 8", a thickness of web not greater than 2% of the depth and a flange width not greater than 44% of the depth.

5. A rolled solid web I-beam having a depth not over 8" and not under 6", a thickness of web not greater than 2.2% of the depth, and a flange width not greater than 48.4% of the depth.

6. A rolled solid web I-beam having a depth not over 6" and not under 4", a thickness of web not greater than 2.8% of the depth, and a flange width not greater than 56.4% of the depth.

7. A rolled solid I-section beam having a relatively deep, thin web, the depth being not over 12" and not under 4" and the thickness of web being not greater than 1.8% to 2.8% of the depth and having a relatively wide and thin flange, the width whereof is not greater than 39.6% to 56.4% of the depth of said web, substantially as described.

8. A rolled solid web I-beam having an approximate depth of 12", an approximate thickness of web of .147", and an approximate flange width of 3.083", respectively.

9. A rolled solid web I-beam having an approximate depth of 9", an approximate thickness of web of .125", and an approximate flange width of 2.335", respectively.

10. A rolled solid web I-beam having an approximate depth of 6", an approximate thickness of web of .120", and an approximate flange width of 1.756", respectively.

11. A rolled solid web I-beam having an approximate depth of 4", and an approximate thickness of web of .106", and an approximate flange width of 1.952".

12. A rolled solid web I-beam having a relatively deep, thin web, the depth being not over 12" and not under 4" and the thickness of the web and width of the flanges being proportional to the depth and approximately 1.2% to 2.65% and 25.7% to 48.8% thereof, respectively, substantially as described.

13. A rolled solid I-section beam having a relatively deep, thin web, the depth being not over 12" and not under 6" and the thickness of web being not greater than

1.8% to 2.8%, respectively, of the depth and having a relatively wide and thin flange, the width whereof is not greater than 39.6% to 56.4%, respectively, of the depth of said web, intermediate sizes having maximum limits in proportion therebetween, substantially as described.

14. A rolled solid web I-beam having a relatively deep, thin web, the depth being over 10" and not over 12", and the thickness of the web and width of the flanges being proportional to the depth and approximately 1.20% to 25.7% thereof, respectively, for a depth of 12", substantially as described.

15. A rolled solid web I-beam having a relatively deep, thin web, the depth being not under 8" and not over 10" and the thickness of the web and width of the flanges being proportional to the depth and approximately 1.4% and 25.9% thereof, respectively, for a depth of 9", substantially as described.

16. A rolled solid web I-beam having a relatively deep, thin web, the depth being under 8" and not under 6", and the thickness of the web and width of the flanges being proportional to the depth and approximately 2% and 29.2% thereof, respectively, for a depth of 6", substantially as described.

17. A rolled solid web I-beam having a relatively deep, thin web, the depth being under 6" and the thickness of web and width of flanges being proportional to the depth and approximately 2.65% and 48.4% thereof, respectively, for a depth of 4", substantially as described.

18. A rolled solid web I-beam having a relatively deep, thin web, the depth being not under 4" and not over 12" and the thickness of the web and width of the flanges being proportional to the depth and approximately 1.2% and 25.7% thereof, respectively, for a depth of 12", substantially as described.

19. A rolled solid web I-beam having a relatively deep, thin web, the depth being over 10" and not over 12", and the thickness of the web being proportional to the depth and approximately 1.20% thereof for a depth of 12", substantially as described.

20. A rolled solid web I-beam having a relatively deep, thin web, the depth being not under 8" and not over 10" and the thickness of the web being proportional to the depth and approximately 1.4% thereof for a depth of 9", substantially as described.

21. A rolled solid web I-beam having a relatively deep, thin web, the depth being under 8" and not under 6", and the thickness of the web being proportional to the depth and approximately 2% thereof for a depth of 6", substantially as described.

22. A rolled solid web I-beam having a

relatively deep, thin web, the depth being under 6", and the thickness of web being proportional to the depth and approximately 2.65% thereof, for a depth of 4", substantially as described.

70

23. A rolled solid web I-beam having a relatively deep, thin web, the depth being not over 12" and not under 4", and the thickness of the web being not greater than 1.8% to 3 1/3% of the depth, substantially as described.

75

24. A rolled solid web I-beam having a relatively deep, thin web, the depth being over 10" and not over 12", and the thickness of the web being not greater than 1.8% of the depth.

80

25. A rolled solid web I-beam having a depth not over 10" and not under 8", and a thickness of web not greater than 2% of the depth.

85

26. A rolled solid web I-beam having a relatively deep, thin web, the depth being under 8" and not under 6", and the thickness of the web being not greater than 2.2% of the depth.

90

27. A rolled solid web I-beam having a relatively deep, thin web, the depth being under 6" and the thickness of web being not greater than 3 1/3% of the depth.

95

28. A rolled solid web I-beam of a transverse strength and weight per foot suitable for replacing wooden joists for floor construction and having its web thickness not greater than the stated proportion of its depth.

100

29. A rolled solid web I-beam of a transverse strength and weight per foot suitable for replacing wooden joists for floor construction and having its flange width not greater than 2" plus one-sixth of its depth.

105

30. A rolled solid I-section beam having a relatively deep, thin web, the depth of the beam being under 12" and the thickness of the web being within about 1.2% to 3 1/3% of the depth, and having a relatively thin flange, the width whereof is approximately sixteen to twenty times the thickness of said web, substantially as described.

110

31. A metal beam characterized by the fact that it is formed by rolling, with a thin, deep web and flanges all integral and continuous throughout, said beam having web and flanges thinner than customary for beams of the same depth and having a transverse strength in excess of that of a rectangular wooden rafter or joist of usual dimensions and having approximately the same weight per foot.

115

32. A metal beam characterized by the fact that it is formed by rolling, with a web and flanges all integral and continuous throughout, the web thickness of said beam being not over one-tenth of an inch plus one one-hundred-and-twentieth of its depth, and the transverse strength of said beam

120

125

130

being in excess of that of a commercial wooden rafter or joist having approximately the same weight per foot.

33. A metal beam characterized by the fact that it is formed by rolling with a thinner than customary web and a proportionally narrower flange width and having its depth, flange width and weight approximating those of a commercial wooden rafter or joist, and its transverse strength in excess of said rafter or joist, said beam being approximately as strong in proportion to its weight as standard rolled metal beams of the same depth.
34. A metal beam characterized by the fact that its web is rolled continuous and integral with its flanges and measurably thinner in proportion to its depth than has

heretofore been customary, said beam having less than half the weight of existing rolled integral solid web beams of the same depth and over twice the transverse strength of existing rolled integral solid web beams of the same weight.

35. A metal beam characterized by the fact that its web is rolled integral with its flanges and proportionately thinner than has heretofore been rolled, said beam being less than one-half the weight and nearly the same resistance to flexure characteristic in proportion to its weight as existing rolled solid web beams of similar depth.

In testimony whereof, I have signed my name to this specification.

JAMES S. LOCHHEAD.
